UNITED STATES PATENT OFFICE.

ALONZO K. FERRIS, OF NEW YORK, N. Y.

GAME APPARATUS.

No. 830,424.

Specification of Letters Patent.

Patented Sept. 4, 1906.

Application filed June 15, 1905. Serial No. 265,391.

To all whom it may concern:

Be it known that I, ALONZO K. FERRIS, a citizen of the United States, residing at Manhattan borough, in the city and county of 5 New York, and State of New York, have invented new and useful Improvements in Game Apparatus, of which the following is a specification.

This invention aims to provide new and 10 novel means whereby the game of roulette can be played by dispensing with costly machinery and removing it from scenes of temptation and dissipation and placing it economically in the realm of sociability.

15 Roulette, as known, requires an expensive apparatus, comprising a wheel or a movable bottom with a ball and other details.

This invention relates to an apparatus for playing roulette, said apparatus consisting 20 of a pack of cards instead of an expensive wheel and appurtenances named. These cards might be called "wheel-cards." They are numbered or marked to correspond with the numbers or marks on a roulette-wheel. 25 These cards having been shuffled and then drawn or turned, the number or character appearing is treated the same as a number or character of a roulette-wheel at which the ball has come to rest.

30 In describing the invention in detail reference is had to the accompanying drawings, wherein is shown, by way of example, a game apparatus in accordance with this invention, and in which—

35 Figure 1 is a view of the lay-out section, and Fig. 2 a view of the wheel-section.

The lay-out section, as shown by way of example, consists of a series of cards indicated by the reference characters 1, 2, 3, 4, 5, 6, 7, 40 8, 9, 10, 11, and 12. The cards 1 to 5 and 7 to 12 are provided with suitable indications, and the cards 6 are each provided with a series of consecutive numbers. The cards 6 may be alternately colored, if desired.

45 The wheel-section consists of a series of cards indicated by the reference characters 13, 14, 15, 16, and 17. The cards 13 and 14 are consecutively numbered, and their numbers correspond with the numbers of the 50 cards 6 of the lay-out section. The cards 13 are differently colored from that of the cards 14. The cards 15, 16, and 17 are provided with suitable indications which associate with the cards 7, 11, and 12 of the lay-out 55 section.

The lay-out can be formed in any suitable way, as by being marked on a board or by cards or in any other manner. A practical way is to have a suitable number of cards, some of which are wheel-cards and the other 60 of which are used to form the lay-out. This forms a practical, cheap, and easily-arranged device. The lay-out cards are spread face up to represent the lay-out of roulette. The player or players then put their stakes as 65 usual in a roulette lay-out. The wheel-cards are then shuffled and a card is turned or drawn. The number or face that appears on the draw or turn of a card is treated the same as the indication at a wheel made by a ball 70 where it comes to rest.

The number of cards is of course not limited to any given figure; but a practical and satisfactory device has been made as follows: A pack of fifty-four cards was made up containing fourteen cards for the lay-out and thirty-nine wheel-cards, as also one card containing rules. Such a pack forms the roulette apparatus complete and can be conveniently sold, handled, and carried, as in the 75 case of an ordinary pack of cards. The lay-out cards can be spread on a table, as stated, and the wheel cards being shuffled one card can then be turned or drawn, as stated. The card of rules may be kept at hand for reference as may be required.

Although the apparatus is designed as a substitute for the ordinary roulette apparatus now in general use, so that the game of roulette can be played by dispensing with 90 costly machinery and removing it from scenes of temptation and dissipation and placing it economically within the realm of sociability, yet a game apparatus in accordance with this invention is adapted for any 95 purposes wherein it is found applicable.

What I claim as my invention, and desire to secure by Letters Patent, is—

1. A game apparatus comprising two sets of cards, certain of the cards thereof provided with a plurality of consecutive numbers alternately arranged upon different colored backgrounds with respect to each other, and the remaining cards of said set having suitable indications thereon, the other set of 100 cards having certain thereof alternately colored with respect to each other and further provided with numbers associating with the consecutive numbers of the other set of 105 cards, the remaining cards of said second set 110

of cards having suitable indications associating with certain of the indications of the first set of cards.

2. A game apparatus comprising a lay-out section provided with a series of consecutive numbers, each number arranged upon an alternately-colored background with respect to each other, said lay-out section further provided with suitable indications, a plurality of 5 cards alternately colored with respect to each other and each provided with a number, said numbers of the cards associating with the numbers of the lay-out section, and a plurality of cards having suitable indications 10 associating with certain of the indications of the lay-out section.

3. A game apparatus comprising a set of cards, certain of the cards of said set consecutively numbered and alternately colored, 20 the remaining cards of said set colored in a different manner from the consecutively-numbered cards and each provided with a suitable indication, and a lay-out section having a portion thereof consecutively numbered 25 with the numbers thereof corresponding to the consecutively-numbered cards, the numbers of the lay-out section having colored backgrounds corresponding to the colors of the consecutively-numbered cards, and said 30 lay-out section further provided with suitable indications, certain of said indications associating with the indications of the cards and having backgrounds corresponding to the background of the cards provided with the 35 indications.

4. A game apparatus comprising wheel-cards, certain of which are alternately colored and consecutively numbered, and lay-out cards, certain of which are colored to correspond 40 with the colored wheel-cards and consecutively numbered to correspond with the numbered wheel-cards.

5. A game apparatus comprising wheel-cards, certain of which are alternately colored and consecutively numbered, and lay-out cards consecutively numbered to correspond 45 with the numbered wheel-cards.

6. A game apparatus comprising a lay-out section provided with a plurality of series of 50 consecutive numbers, the numbers of each series of numbers arranged upon an alternately-colored background with respect to each other, and a plurality of cards alternately colored with respect to each other and 55 each provided with a number, said colors and numbers of the cards associating with the colors and numbers of the plurality of series of numbers of the lay-out section.

7. A game apparatus consisting of a lay-out section and a wheel-section, said lay-out section comprising a series of cards, certain of which are each provided with a series of

consecutive numbers, the numbers of each series of numbers arranged upon an alternately-colored background with respect to each other and said wheel-section consisting of a plurality of cards alternately colored with respect to each other and each provided with a number, said colors and numbers of the cards of the wheel-section associating 65 with the colors and numbers upon the cards of the lay-out section.

8. A game apparatus consisting of a lay-out section and a wheel-section, said lay-out section comprising a series of cards, certain of which are each provided with a series of consecutive numbers, the numbers of each series of numbers arranged upon an alternately-colored background with respect to each other and said wheel-section consisting of a plurality of cards alternately colored with respect to each other and each provided with a number, said colors and numbers of the cards of the wheel-section associating 70 with the colors and numbers upon the cards of the lay-out section, said lay-out section further having certain of its cards provided with suitable indications, and said wheel-section further having certain of its cards provided with suitable indications associating with the 75 colors and numbers upon the cards of the lay-out section.

9. A game apparatus comprising a lay-out section provided with a series of consecutive numbers, said lay-out section further provided with suitable indications, a plurality of cards alternately colored with respect to each other and each provided with a number, said numbers of the cards associating with the numbers of the lay-out section, and a plurality of cards having suitable indications 80 associating with certain of the indications of the lay-out section.

10. A game apparatus comprising a lay-out section provided with a series of numbers, each number arranged upon a colored background, said lay-out section further provided with suitable indications, a plurality of cards, each provided with a number, each number of the cards arranged upon a colored 85 background, said colors and numbers of the cards associating with the colors and numbers of the lay-out section, and a plurality of cards having suitable indications associating 90 with certain of the indications of the lay-out section.

In testimony whereof I have hereunto set my hand in the presence of two subscribing witnesses.
